CLAIM

The ornamental design for a tire, as shown and described.

DESCRIPTION

FIG. 1 is a side perspective view of a tire showing our new design, it being understood that the tread pattern is repeated throughout the circumference of the tire, the opposite side being the same as that shown;

FIG. 2 is a front elevational view of the tire;

FIG. 3 is an enlarged fragmentary view of the tire taken along line 3-3 of FIG. 2; and,

FIG. 4 is a side elevational view of the left side of the tire, the opposite side being the same as that shown.

The broken lines depict environmental subject matter that forms no part of the claimed design.

1 Claim, 4 Drawing Sheets
